F. CABALKA

CORN FODDER KNIFE

Filed Dec. 11, 1922

Frank Cabalka,

BY
Geo. F. Kimmel,
ATTORNEY.

UNITED STATES PATENT OFFICE.

FRANK CABALKA, OF GEDDES, SOUTH DAKOTA.

CORN-FODDER KNIFE.

Application filed December 11, 1922. Serial No. 606,169.

To all whom it may concern:

Be it known that I, FRANK CABALKA, a citizen of the United States, residing at Geddes, in the county of Charles Mix and State of South Dakota, have invented certain new and useful Improvements in Corn-Fodder Knives, of which the following is a specification.

This invention relates to fodder cutters, and has for one of its objects to provide a device of this character of increased simplicity and efficiency.

With these and other objects in view, the invention consists in certain novel features of construction as hereinafter shown and described and then specifically pointed out in the claims, and in the drawings illustrative of the preferred embodiment of the invention—

20 Figure 1 is a side elevation, partly in section.

Figure 2 is a plan view.

Figure 3 is a transverse section on the line 3—3 of Fig. 2.

25 Figure 4 is a transverse section on the line 4—4 of Fig. 2.

The improved device comprises a base or platform portion 10 having a longitudinal opening or slot 11 and supported upon 30 transverse cleats 12 and with an encompassing "drop" portion 13.

The cleats 12 serve as "heads" to support leg members 14 which are bolted thereto, as at 15.

35 Attached to the upper face of the platform 10 near one end is a divided standard 16 between whose sides a cutting blade or knife 17 is pivoted at 18.

The knife extends at its free end beyond 40 the opposite end of the platform and is provided with hand grip members 19.

Attached to the platform 10 adjacent the handle end of the blade are spaced guides 20, 21 supported by braces 22 and 23 from 45 the platform and between which the knife is received and guided during the cutting action.

50 Preferably a steel ledger strip 24 will be attached to one inner face of the opening 11 to coat with the cutting edge of the knife, as illustrated in Figures 2, 3 and 4.

The improved device is simple in construction, can be manufactured entirely of wood except the blade and the bracket 16 and guides 20 and 21.

The improved device may be of any desired size or capacity and will be found very efficient for cutting up corn stalks and other fodder material for packing in silos and for feeding direct.

The preferred embodiment of the invention is disclosed in the drawings and set forth in the specifications, but it will be understood that modifications within the scope of the claims may be made in the construction without departing from the principle of the invention or sacrificing any of its advantages.

Having thus described the invention what is claimed as new is:

1. An apparatus of the class described comprising a supporting platform having a longitudinally directed slot and holding cleats transversely beneath the platform and transversely of the slot, a bracket device including spaced sides with one side mounted on said platform adjacent to one end of said slot and the other side bearing upon the adjacent cleat within the slot, guide standards formed with spaced sides disconnected at their upper ends, with one side attached at its lower end to said platform and the other side attached to the adjacent cleat within the slot, a ledger plate located within the slot and attached to one side of the same, the terminals of the plate being held respectively at the ends beneath the lower end at one side of the guide member and one side member of the standard and bearing upon the cleats, and a knife member pivoted at one end to said bracket and operating between said guide standards, the cutting edge of said knife coacting with said ledger plate.

2. An apparatus of the character set forth having a platform with a support and connecting cleats, said platform having a slot transversely to said cleats; guides, and a divided bracket connected respectively to said cleats near the opposite ends of said slot, a ledger blade resting at its ends on said cleats and against one wall of the slot, and a movable blade pivoted in said bracket and working in said slot and guides.

In testimony whereof, I affix my signature hereto.

FRANK CABALKA.
